OFFSET ALIGNING TYPE-MATRIX HOLDER

Philip P. Merrill, Evanston, Ill., assignor to Ludlow Typograph Company, Chicago, Ill., a corporation of Illinois

Application October 26, 1932. Serial No. 639,717

18 Claims. (Cl. 199—47)

My invention relates to holders for matrices employed in the casting of type slugs bearing lines of printing characters and being provided for receiving and holding a number of detached matrices in selected relation thereby forming a composite matrix adapted to co-operate with a mold to produce the desired line of printing characters on the slug formed in the mold.

One of my objects is to provide a construction of holder wherein provision is made for the relative shifting of the matrices crosswise of the line thereof for producing the desired alignment of the character impressions in the matrices, particularly where the line of matrices is composed of matrices from different fonts the character impressions of which are located at different distances from the ends of the matrices.

Another object is to provide a construction whereby the character impressions in the matrices may be aligned as stated and the adjustment of the parts for producing such alignment, maintained, until purposely disturbed, adapting the holder for the proper aligning of the character impressions in the composing of different lines of matrices from the same selected fonts; and other objects as will be manifest from the following description.

Referring to the accompanying drawings in which I have illustrated my invention as embodied in a matrix holder provided as a part separable from the machine in which the type slugs are cast, and which, in use in connection with the mold, is temporarily applied to operative position relative to the mold:

Figure 1 is a broken plan view of a matrix holder embodying my invention and showing it in position for casting in a slug-casting machine.

Figure 2 is a broken view in vertical sectional elevation of the holder and slug-casting machine, the section being taken at the irregular line 2 on Fig. 1 and viewed in the direction of the arrow.

Figure 3 is an enlarged section taken at the line 3—3 on Fig. 1 and viewed in the direction of the arrows.

Figure 4 is an enlarged section taken at the line 4—4 on Fig. 1 and viewed in the direction of the arrows.

Figure 5 is an enlarged broken section taken at the line 5 on Fig. 1 and viewed in the direction of the arrow.

Figure 5^a is an enlarged broken section taken at the line 5^a on Fig. 1 and viewed in the direction of the arrow.

Figure 6 is a section taken at the line 6 on Fig. 5 and viewed in the direction of the arrow.

Figure 7 is a bottom plan view of the holder of the preceding figures showing a line of matrices therein before the means for aligning the character impressions in the matrices have been operated.

Figure 8 is a similar view of the holder showing the matrices positioned by said means for aligning the character impressions.

Figures 9 and 10 are enlarged face views of certain of the matrices of Figs. 7 and 8 showing them in the positions illustrated in Figs. 7 and 8, respectively.

Figure 11 is a top plan view of a modification of the holder of the preceding figures, with a line of matrices therein, but viewing the edges of the matrices opposite those containing the character impressions, this view showing the matrices before the latter are relatively shifted into a position for aligning their character impressions.

Figure 12 is a view like Fig. 11 and of the construction therein shown, showing the matrices relatively shifted into position for aligning their character impressions.

Figure 13 is a bottom plan view of the holder of Figs. 11 and 12 with the matrices omitted.

Figure 14 is a broken plan sectional view of the holder of Figs. 11—13, the section being taken at the line 14 on Fig. 15 and viewed in the direction of the arrow; and

Figure 15, an enlarged sectional view taken at the line 15 on Fig. 12 and viewed in the direction of the arrow.

Referring to Figs. 1 to 10, inclusive, the matrix holder represented at 16 and embodying my invention as hereinafter described, co-operates, in accordance with common practice, with a mold member 17 of a line-slug casting machine as commonly provided, presenting a mold cavity 18 in which the shank of the line-slug to be produced is cast, the metal to form the slug being projected upwardly into the mold cavity 18 through its open bottom and against the line of matrices in the holder, which latter is accurately positioned relative to the mold cavity 18 by a stop 19 provided on the bed 20 of the machine and containing an opening 21 into which the mold member 17 extends.

The matrix holder shown comprises a frame-like body portion 22 presenting an opening 23 in which the matrices 24 against which the metal introduced into the mold cavity 18 is cast to form the line of printing characters on the slug, are positioned, one of the side bars of the frame 22 and represented at 25 being provided with a

65

70

75

80

85

90

95

100

110

scale 26 presenting graduations corresponding with the different lengths of finished slugs to be produced, in accordance with common practice.

The opening 23 in the frame 22 is of a width 5 somewhat greater than the length of the portions of the matrices which extend into the opening 23 and the bottom edges of which contain the character impressions represented at 27, whereby the matrices may be shifted relative to each other 10 crosswise of the line thereof.

The matrix holder also comprises a block 28 15 slidable in the opening 23 and forming the movable end quad of the holder and by which the line of matrices is clamped against the stationary end piece 29 of the frame 22, the end quad 28 being operated by means of a screw shaft journaled, but immovable lengthwise, in the other stationary end piece 31 of the frame and screwing 20 at its threaded end in a threaded opening 32 in the end quad 28.

In accordance with this particular embodiment of my invention, the frame 22 is provided with an apron 33 which extends in, and lengthwise of, the opening 23 along the inner side of the bar portion 34 which is preferably recessed lengthwise as represented at 35, and which, with the bar portion 25, forms the longitudinal side portions of the frame 22, the apron 33 thus extending lengthwise along the line of matrices in 30 the holder and opposing the adjacent ends of the matrices.

The apron 33 is supported at its opposite ends on trunnions 36 journaled in the end pieces 29 and 31 and located adjacent the upper edge of 35 the apron thus adapting the apron to be swung toward and away from the matrices while maintaining parallelism with the side bar 25.

The apron 33 is swung on its trunnions 36 to 40 relatively shift the matrices, by means of a knob 37 journaled on a stud 38 secured to the end piece 29 and containing in its inner face a cam groove 39 shown as of circular shape and disposed eccentric to the stud 38 and into which a pin 40 on the apron 33 and projecting lengthwise 45 thereof beyond an end of the latter, extends, the pin 40 extending through an arcuate slot 41 in the end piece 29. Thus by rotating the knob 37 the apron 33 will be swung in one direction or the other depending upon the direction of rotation 50 of the knob, the arrangement of the parts being such, as shown, that these parts remain in the position to which they are operated until the operator again exerts turning force against the knob.

55 In the use of the holder shown the matrices are inserted into the opening 23 seating at the upper portions of their ends on the frame sides 34 and 25, and those of one font, as for example the caps shown in the drawings, slid crosswise of the 60 holder to abut against the apron 33 and those of the other font, as for example the lower case letters shown in the drawings, slid in the opposite direction to abut against the inner face of the frame side 25. In this position of the 65 matrices the lower edges of the caps, as will be noted from Figs. 8 and 9, extend above the corresponding edges of the lower case letters and thus out of alignment therewith. The operator then preferably slightly tightens the end quad 70 28 against the matrices and rotates the knob 37 to swing the apron 33 toward the matrices thereby moving the cap matrices transversely of the line thereof and relative to the lower case matrices into a position in which the lower edges 75 of the caps and of the lower case letters are in

accurate alignment as shown in Figs. 8 and 10, the quad screw 30 then being rotated to clamp the end quad against the matrices with the desired pressure.

The apron 33 and the operating mechanism therefor remain in the position to which they are operated as above explained and thus when a new composition comprising selected matrices from these same fonts is to be produced, it is unnecessary to readjust the apron, but merely 80 to position the matrices of the different fonts against the frame side 25 and the apron 33, respectively. A scale represented at 33^a and provided about the periphery of the knob 37 and co-operating with a marking 33^b, shown as a line, on the end piece 29, serves as a means to be used when desired, whereby the apron 33 may be adjusted into a predetermined position before the matrices are assembled with the holder and known to be the proper position of adjustment 85 for a line of matrices selected from different fonts.

90 Referring to the holder construction shown in Figs. 11 to 15, inclusive, it comprises a frame 42, like the frame 22, and presenting stationary end pieces 43 and 44 and side members 45 and 46 defining a matrix-receiving opening 47, the side member 45 being provided with a scale 48, like the scale 26, a sliding end quad block 49 in the opening 47, and a quad screw 50 like the 95 screw 30.

100 In this construction, instead of providing a swinging apron for producing relative sliding of the matrices, a slid able bar represented at 51 is provided, this bar, which extends beneath the frame side 46, being projectable laterally for effecting the aligning of the character impressions in the matrices represented at 52. The ends of the end pieces 43 and 44, adjacent the bar 51, 110 contain notches 53 and 53^a, respectively, to receive the bar 51 which is confined between the frameside 46 and lugs 54 projecting laterally from the lower portions of the end pieces 43 and 44.

115 The bar 51 is shown as provided on its upper face with a rib, or tongue, 55 which extends at a sharp angle to the median line of the bar 51 as shown, this rib being located in a similarly inclined groove 56 in the under surface of the frameside 46. Thus when the bar 51 is 120 moved lengthwise it moves toward or away from the opening 47 depending on the direction in which it is moved endwise, while remaining parallel at all times with the frame 42.

125 The construction also comprises means for moving the bar 51 lengthwise and comprising a threaded stud 57 secured in the end piece 43 to extend outwardly therefrom at one end in a direction lengthwise of the holder, and a nut 58 threaded on the stud 57 and extending into a 130 slot 59 in the side of the bar 51.

135 The bar 51 performs the same function as that above described of the apron 33 and by reason of the arrangement of the parts as described the bar 51 remains in the position to which it is 140 operated until the nut is again actuated. A scale represented at 60 and provided on the underside of the bar 51 and co-operating with a marking 61, shown as a line, on one of the lugs 145 54, serves as a means, to be used when desired, whereby the bar 51 may be adjusted into a predetermined position before the matrices are assembled with the holder and known to be the proper position of adjustment for a line of matrices selected from different fonts. 150

- While the constructions shown are above described in connection with their use with matrices from different fonts in which the lower edges of the character impressions are spaced 5 different distances from the ends of the matrices, it will be understood that these constructions also may be utilized where the upper edges of the character impressions are to be aligned. Furthermore, the constructions present utility in 10 the composing of matrices from a single font inasmuch as by adjusting the apron 33 in the one construction and the bar 51 in the other, outwardly, a relatively wide opening to receive the matrices is provided, permitting of their ready 15 introduction into the opening, the proper alignment of the matrices being effected by adjusting the apron, or bar, as the case may be, inwardly to slide all of the matrices against the opposite side member of the offset holder.
- 20 While I have illustrated and described certain particular constructions embodying my invention, I do not wish to be understood as intending to limit it thereto as the same may be variously modified and altered and the invention embodied in other forms of structure without departing from the spirit of my invention.
- What I claim as new, and desire to secure by Letters Patent, is:
1. A type-matrix holder comprising a member 30 in which the matrices are positioned to extend in a line and having opposing parallel side wall members one of which is movable toward and away from the other thereof into different set positions, means whereby said movable side-wall member, in its movements, is maintained parallel with the other of said side-wall members and means for holding said movable side wall member against movement in either direction out of any position of adjustment while permitting removal of said matrices.
  2. A type-matrix holder comprising a member 35 in which the matrices are positioned to extend in a line and having opposing parallel side wall members one of which is movable toward and away from the other thereof, and means for moving said movable side wall member toward the other of said side-wall members in parallelism therewith and holding said movable side wall member against movement in either direction out of any position of adjustment while permitting removal of said matrices.
  3. A type-matrix holder comprising a member 40 in which the matrices are positioned to extend in a line and having opposing parallel side wall members one of which is movable toward and away from the other thereof, and means whereby said movable side-wall member, in its movements, is maintained parallel with the other of said side-wall members, and means independent of the matrices for holding said movable side-wall member in adjusted position.
  4. A type-matrix holder comprising a member 45 in which the matrices are positioned to extend in a line and having opposing parallel side wall members one of which is movable toward and away from the other thereof, and means for moving said movable side wall member toward the other of said side-wall members in parallelism therewith and holding said movable side-wall member in adjusted position independent of the matrices.
  5. A type-matrix holder comprising a member 50 in which the matrices are positioned to extend in a line, and adjustable means adapted to co-operate with the adjacent ends of certain of the
- matrices and serve as a means for positioning the same transversely of the line thereof, said means being adapted to remain in adjusted position after removal of the matrices.
6. A type-matrix holder comprising a frame-like member presenting an opening in which the matrices are positioned to extend in a line, said opening being of greater width than the length of those portions of the matrices which extend into said opening, and adjustable means adapted to co-operate with the adjacent ends of certain of the matrices and serve as a means for positioning the same transversely of the line thereof, said means being adapted to remain in adjusted position after removal of the matrices. 80
  7. A type-matrix holder comprising a member in which the matrices are positioned to extend in a line, means for positioning certain of the matrices transversely of the line thereof comprising a second member positioned to extend alongside of the line of matrices and movable in parallelism with the opposite side of said first-named member, and means for holding said second member in the position to which it is moved after removal of the matrices. 85
  8. A type-matrix holder comprising a member in which the matrices are positioned to extend in a line, means for positioning certain of the matrices transversely of the line thereof comprising a second member positioned to extend alongside of the line of matrices and movable in parallelism with the opposite side of said first-named member, and means for moving said second member in parallelism with the opposite side of said first-named member and holding it in the position to which it is moved after removal of the matrices. 90
  9. A type-matrix holder comprising a member in which the matrices are positioned to extend in a line, and matrix-positioning means comprising a swinging apron positioned to extend alongside of the line of matrices and co-operate with the adjacent ends of certain only of said matrices, for the purpose set forth. 95
  10. A type-matrix holder comprising a member in which the matrices are positioned to extend in a line, and matrix-positioning means comprising a swinging apron positioned to extend alongside of the line of matrices and co-operate with the adjacent ends of certain only of said matrices, and means for holding the apron in the position to which it is swung. 100
  11. A type-matrix holder comprising a member in which the matrices are positioned to extend in a line, and matrix-positioning means comprising a swinging apron positioned to extend alongside of the line of matrices and co-operate with the adjacent ends of certain only of said matrices and means for swinging said apron and holding it in the position to which it is swung. 110
  12. A type-matrix holder comprising a member in which the matrices are positioned to extend in a line, and matrix-positioning means comprising a swinging apron positioned to extend alongside of the line of matrices and co-operate with the adjacent ends of certain of said matrices, a projection on said apron eccentric of the axis about which said apron swings, a rotary member on said first-named member and cam means actuated by said rotary member and engaging said pin for swinging said apron. 115
  13. A type-matrix holder comprising a member in which the matrices are positioned to extend in a line, and matrix-positioning means comprising a swinging apron positioned to swing 120
  14. A type-matrix holder comprising a member in which the matrices are positioned to extend in a line, and matrix-positioning means comprising a swinging apron positioned to extend alongside of the line of matrices and co-operate with the adjacent ends of certain only of said matrices and means for swinging said apron and holding it in the position to which it is swung. 125
  15. A type-matrix holder comprising a member in which the matrices are positioned to extend in a line, and matrix-positioning means comprising a swinging apron positioned to extend alongside of the line of matrices and co-operate with the adjacent ends of certain only of said matrices and means for swinging said apron and holding it in the position to which it is swung. 130
  16. A type-matrix holder comprising a member in which the matrices are positioned to extend in a line, and matrix-positioning means comprising a swinging apron positioned to extend alongside of the line of matrices and co-operate with the adjacent ends of certain of said matrices, a projection on said apron eccentric of the axis about which said apron swings, a rotary member on said first-named member and cam means actuated by said rotary member and engaging said pin for swinging said apron. 135
  17. A type-matrix holder comprising a member in which the matrices are positioned to extend in a line, and matrix-positioning means comprising a swinging apron positioned to swing 140
  18. A type-matrix holder comprising a member in which the matrices are positioned to extend in a line, and matrix-positioning means comprising a swinging apron positioned to extend alongside of the line of matrices and co-operate with the adjacent ends of certain only of said matrices and means for swinging said apron and holding it in the position to which it is swung. 145
  19. A type-matrix holder comprising a member in which the matrices are positioned to extend in a line, and matrix-positioning means comprising a swinging apron positioned to swing 150

- alongside of the line of matrices and co-operate with the adjacent ends of certain of said matrices, a projection on said apron eccentric of the axis about which said apron swings, a rotary member on said first-named member and cam means actuated by said rotary member and engaging said pin for swinging said apron comprising an arcuate cam groove eccentric of the axis of rotation of said rotary member and into which 5 said pin extends.
14. A type-matrix holder comprising a member in which the matrices are positioned to extend in a line, matrix-positioning means comprising a bar positioned on said member to be moved toward and away from the matrices in parallelism with the opposite side of said member, and means independent of the matrices for holding said bar 15 in the position to which it is moved.
15. A type-matrix holder comprising a member in which the matrices are positioned to extend in a line, and matrix-positioning means comprising a bar positioned on said member to extend lengthwise of, and be movable along, the line of matrices and cam means between said bar 20 and member operating to bodily shift said bar crosswise of the line of matrices in the lengthwise movement of said bar.
16. A type-matrix holder comprising a mem- 25

ber in which the matrices are positioned to extend in a line, and matrix-positioning means comprising a bar positioned on said member to extend lengthwise of, and be movable along, the line of matrices, cam means between said bar and member operating to bodily shift said bar crosswise of the line of matrices in the lengthwise movement of said bar and means for moving said bar lengthwise thereof.

17. A type-matrix holder comprising a member in which the matrices are positioned to extend in a line, and matrix-positioning means comprising a bar positioned on said member to extend lengthwise of, and be movable along, the line of matrices and cam means between said bar and member operating to bodily shift said bar crosswise of the line of matrices in the lengthwise movement of said bar and comprising tongue and groove portions inclined relative to said bar.

18. A type-matrix holder comprising spaced side members to align matrices, one of said members mounted for parallel motion toward and away from the other thereof, and adjustable means for preventing motion of said movable member in one direction from any set position thereof while permitting the removal of the matrices.
